[57] CLAIM

The ornamental design for a combined hanging display case and clock, substantially as shown and described.

DESCRIPTION

FIG. 1 is a prospective view of a combined hanging display case and clock showing my new design.

FIG. 2 is a front elevational view, the opposite back view being a mirror image thereof.

FIG. 3 is a top plan view.

FIG. 4 is a right side elevational view.

FIG. 5 is a left side elevational view.

FIG. 6 is a bottom plan view.
